UNITED STATES PATENT OFFICE.

WILLIAM C. FOLEY, OF CHICAGO, ILLINOIS.

DESIGN FOR A SPOOL-HOLDER FOR SEWING-MACHINE STANDS.

No. 39,754.

Specification for Design.

Patented Jan. 12, 1909.

Application filed April 13, 1908. Serial No. 426,914. Term of patent 7 years.

To all whom it may concern:

Be it known that I, WILLIAM C. FOLEY, a citizen of the United States of America, residing at Chicago, in the county of Cook and State of Illinois, have invented a new, original, and ornamental Design for Spool-Holders for Sewing-Machine Stands, of which the following is a specification, reference being had to the accompanying drawing, forming a part thereof and which represents a perspective view of my new design.

The salient features of my design comprise a flat base having straight ends, a straight side and a curved side opposite to

such straight side. At one end of the base a raised pin cushion and holding tray are located, and the balance of the base is provided with a series of vertical prongs for holding spools of thread.

I claim:

The ornamental design for a spool holder for sewing machine stands, as shown and described.

WILLIAM C. FOLEY.
